LIQUID FUEL COMBUSTION APPARATUS

Gustaf Erik Björklund, Lidingo, Sweden, assignor
to Svenska Aktiebolaget Gasaccumulator,
Stockholm, Sweden, a corporation of Sweden

Application March 21, 1934, Serial No. 716,554
In Sweden December 13, 1933

12 Claims. (Cl. 158—36)

The present invention relates to fuel combustion and has particular reference to liquid fuel combustion apparatus of the kind in which liquid fuel is vaporized alternatively in different fuel vaporizers to provide a continuous supply of vaporized fuel for combustion in a burner. Still more particularly, the invention relates to fuel combustion apparatus for use in cook stoves and the like of the kind disclosed in the application of Gustaf Dalen, Serial No. 695,882, filed October 30, 1933.

In apparatus of the kind above referred to, liquid hydrocarbon fuel, such, for example, as fuel oil, is vaporized by being brought into contact with a hot vaporizing surface and, as a result of the vaporization of the fuel, coke-like deposits of heavy hydrocarbon are formed on the vaporizing surface, which deposits in time interfere with the proper vaporization of the fuel. In order to overcome the difficulties arising because of the formation of coke deposits, a plurality of vaporizing surfaces in separate vaporizers are used, which are alternatively employed to supply vaporized fuel to a given combustion device or burner. In such arrangements, the supply of fuel is shifted from an active vaporizer after it has been in use long enough for a coke deposit approaching objectionable magnitude to form, to an inactive vaporizer in which coke deposited during previous activity has been removed by combustion.

In previous forms of apparatus of this character, the shifting of the fuel supply from one to another vaporizer has been effected manually. The kinds of devices for which the fuel combustion apparatus is particularly adapted are ordinarily under the supervision of unskilled operators, and consequently the shifting of the fuel supply at the proper time cannot be relied upon, particularly since the time interval elapsing between the required shifting of position of the fuel supplying apparatus is usually rather long, and consequently the required shifting is relatively easily forgotten.

The general object of the present invention is to provide means whereby the supply of fuel will be automatically directed to different vaporizers in accordance with the requirements of the apparatus.

The manner in which the above and other objects of the invention are attained, together with the more detailed nature of the invention and the advantages to be derived from its use may best be understood from a consideration of the following description of a preferred form of ap-

paratus for carrying the invention into effect. In the accompanying drawings forming a part of this specification:

Fig. 1 is a vertical sectional view, partly in elevation, of apparatus embodying the invention;

Fig. 2 is a side elevation partly in section of part of the apparatus shown in Fig. 1 and looking from the left of Fig. 1; and

Fig. 3 is a section taken on the line 3—3 of Fig. 1.

Referring now particularly to Fig. 1, the invention is shown as applied to the fuel combustion apparatus for a domestic cook stove of the heat accumulating type, although it is to be understood that the invention is not limited in its application to this particular use.

In the apparatus illustrated, a burner is indicated generally at 10, which, insofar as the present invention is concerned, may be of any suitable kind for continuous burning of fuel vapor. In the form illustrated, the burner comprises an outer sleeve 12, an intermediate perforated sleeve 14 and an inner sleeve 16. Air for combustion is admitted through the channel 18 to the interior of sleeve 16, and also is admitted from the chamber 20 to the space between sleeves 12 and 14. Fuel vapor is admitted to the space 22 which communicates with the space between sleeves 14 and 16. The space 22 is provided by a recess or socket in a metal burner base indicated generally at 24, which provides two vaporizing chambers 26 and 28. Chambers 26 and 28 are closed by a suitable cover plate 30 and are provided respectively with openings through which vaporized fuel flows to the space 22 by way of port 36.

Mounted above the vaporizing chambers is a casing 38 providing two chambers (see Fig. 3) 40 and 42, the former being in communication with chamber 26 by way of pipe 44 and the latter being in communication with chamber 28 by way of pipe 46. Chambers 40 and 42 are separated by a partition formed in part by a block-like member 48 having curved contact surfaces 50 and mounted for oscillating movement in the casing 38. Extending transversely from the block 48 are two pipes 52 and 54, the open ends of which are respectively above the pipe connections 44 and 46. The pipes 52 and 54 are in communication with a central passage 56 in block 48 and passage 56 is in communication with a pipe 58 located at the axis of oscillation of block 48. Openings for the admission of air to chambers 40 and 42 are provided at 60 and 62. Pipe 58 is suitably journaled

in cover plate 64 of casing 38 and may also be advantageously journalled in the outer cover plate 66. At its outer end pipe 58 has fixed thereto a receptacle 68, the interior of which is in communication with the pipe, and which is located below a fuel supply nozzle 78 to which fuel is admitted through the pipe 72 from the supply tank 14. Regulation of the amount of fuel is effected by any suitable means as, for instance, the nozzle control member 76 which is advantageously responsive to a thermostat (not shown). A bracket 78 fixed to plate 66 provides a pivot support 80 for an upwardly extending arm 82 at the upper end of which is fastened the transversely extending part 84 provided with spaced arms 86 and 88. The receptacle 68 is located between arms 86 and 88. A pipe 90 is secured to the arm 82 by means of a clamp 92, and the ends of this pipe extend into and serve to support two closed vessels 94 and 96. Vessels 94 and 96 and pipe 90 provide a closed space which is advantageously evacuated of air and is partially filled with a liquid having a relatively moderate vaporizing temperature, such as benzol, such liquid being indicated at 98 in Fig. 2. Extending laterally from the plate 66 are two metal heat conducting members 100 and 102, the outer ends of which are respectively beneath the vessels 94 and 96. The outer ends of members 100 and 102 are preferably provided with surfaces complementary to the surfaces of the vessels 94 and 96. In the embodiment illustrated, vessels 94 and 96 are cylindrical in form and the parts 100 and 102 are curved to the same radius as the cylinders. Parts 100 and 102 are further respectively provided with adjustable screws 104 and 106 adapted to respectively contact vessels 94 and 96.

The operation of the apparatus is as follows: fuel from the nozzle 78 falls into the receptacle 68 from which it flows through pipe 58 to one or the other of the vaporizing chambers 26 or 28 depending upon the position of rotation of the pipe 58 carrying the transverse pipes 52 and 54. The length and position of these latter pipes are such that fuel flowing through pipe 58 will flow only through one or the other of these pipes and not simultaneously through both when the pipes are inclined. Fuel flowing from pipe 52 drops to the vaporizing surface 108 of chamber 26, and fuel flowing from pipe 54 drops to the vaporizing surface 110 of chamber 28. Both of these surfaces are continuously maintained at a temperature sufficiently high to vaporize fuel by conduction of heat through the base 24 from the combustion zone of the burner. A small quantity of air is continuously admitted to both vaporizing chambers through the supply openings 60 and 62, and this relatively small amount of air is continuously drawn through both vaporizing chambers by the draft induced by the burner. When fuel is being directed to one of the vaporizing chambers for vaporization therein, the air flowing through the other, or inactive, chamber provides oxygen for slowly burning away the residual deposit of coke or the like formed by previous active use of the at the moment inactive chamber.

From Fig. 2 it will be evident that the pivot point 80 is located below the center of gravity of the mass represented by the vessels 94 and 96, the liquid contained in them, and the other parts connected to move about the pivot. The position of the vessels 94 and 96 will therefore depend upon the relative mass of liquid in the two vessels, and, depending upon the distribution of the liquid, the parts mounted for oscillation about the pivot

80 will be either in the position shown in Fig. 2 or in an opposed position with the vessel 94 in contact with the part 100 or the adjustment screw 104. With the parts as shown in Fig. 2, the arm 86 of the member 84 will have moved the receptacle 68 to the position shown in this figure, and the pipe 52 will be in the position shown in Fig. 3 for causing the fuel to be delivered to the vaporizing chamber 26. With the movable parts in the positions shown, the vessel 98 will be in heat transmitting relation with the part 102, which is constantly maintained at elevated temperature by heat derived from the burner. The heat supplied to the vessel 96 from the part 102 vaporizes the liquid in the vessel, and the vapor, passing to the colder vessel 94 is condensed therein so that the gradual transfer of the liquid from vessel 96 to vessel 94 takes place. After sufficient liquid has thus been transferred from the lower to the higher vessel, the system of parts oscillating about the pivot point 80 becomes overbalanced and changes position so that the vessel 94 comes in contact with the member 100 and the vessel 96 is moved out of contact with member 102. The heat now transmitted from member 100 to the vessel 94 vaporizes the liquid therein, which flows to and is condensed in vessel 96 until the system is again over-balanced and returns to its original position. It will thus be evident that due to the alternative transmission of heat to the two vessels, the position of the oscillating system of parts including these vessels, is automatically shifted from one to the other of two positions. The length of time required for shifting the position of this system is regulated by means of the adjusting screws 104 and 106 by means of which the position of the liquid containing vessels relative to the parts 100 and 102 may be altered to change the rate of heat transmission through these parts to the vessels. In moving from one to the other of its two positions, the system of oscillating parts comprising the liquid containing vessels moves the receptacle 68 from one to another of two positions, from one of which fuel is directed through pipe 52 to chamber 26, and from the other of which fuel is directed through pipe 54 to chamber 28.

In order to insure the desired quick and positive shifting of the receptacle 68 and associated parts from one to the other of these positions, the arms 86 and 88 are relatively widely spaced apart to provide a lost-motion connection between the two independently movable systems of parts. By providing this lost-motion connection, movement of the parts comprising the liquid containing vessels is initiated upon over-balancing of the parts without resistance from the parts comprising the receptacle 68, and the latter system of parts is moved from one to the other of its positions by either arm 86 or arm 88 after the vessels 94 and 96 and associated parts have moved a considerable distance and built up a substantial amount of kinetic energy. Thus, the effect of variations in frictional resistance in the moving parts where friction is most likely to occur, is substantially eliminated and correct timing of the shifting of position of the parts is obtained.

It will be evident that many variations in the form and arrangement of the parts may be made without departing from the invention, which is to be understood as including all forms of apparatus falling within the terms of the appended claims when construed as broadly as is consistent with the state of the prior art.

What I claim is:

1. In liquid fuel combustion apparatus, two vaporizers adapted to vaporize liquid fuel for combustion in a burner and to be heated by heat derived from the burner, means including a part movable to direct liquid fuel to one or the other of said vaporizers, means comprising two communicating liquid containing vessels mounted to move to different positions in response to changes in the relative amounts of liquid in the two vessels for shifting the position of said movable part, and means for supplying heat alternatively to one or the other of said vessels to vaporize liquid therein.
- 15 2. In liquid fuel combustion apparatus, a burner, two vaporizers in heat conducting relation with said burner for vaporizing liquid fuel for combustion in the burner, means including a part movable to direct liquid fuel to one or the other of said vaporizers, means comprising two communicating liquid containing vessels mounted to move to different positions in response to changes in the relative amounts of liquid in the two vessels for shifting the position of said movable part, and means for supplying heat derived from said burner alternatively to one or the other of said vessels to vaporize the liquid therein.
- 30 3. In liquid fuel combustion apparatus, a burner, two vaporizers in heat conducting relation with said burner for vaporizing liquid fuel for combustion in the burner, means including a part movable to direct liquid fuel to one or the other of said vaporizers, means comprising two communicating liquid containing vessels mounted to move to different positions in response to changes in the relative amounts of liquid in the two vessels for shifting the position of said movable part, and means for conducting heat derived from said burner alternatively to one or the other of said vessels, and means for regulating the rate at which heat is conducted to said vessels.
- 35 4. In liquid fuel combustion apparatus, a plurality of vaporizers adapted to vaporize liquid fuel for combustion in a burner, means including a part mounted to move to different positions to alternatively supply fuel to different vaporizers, means including two communicating closed liquid containing vessels pivoted below the center of gravity of the last-mentioned means to oscillate to one or the other of two positions dependent upon the relative amounts of liquid in the two vessels and motion transmitting means for causing movement of said part from a position supplying fuel to one vaporizer to a position supplying fuel to a different vaporizer due to movement of said vessels from one to the other of said two positions, and means for supplying heat alternatively to one or the other of said vessels to vaporize the liquid in the vessel to which heat is being supplied.
- 50 5. In liquid fuel combustion apparatus, a plurality of vaporizers adapted to vaporize liquid fuel for combustion in a burner, means including a part mounted to move to different positions to alternatively supply fuel to different vaporizers, two evacuated and communicating liquid containing vessels mounted to move to one or the other of two positions dependent upon the relative amounts of liquid in the two vessels, motion transmitting means for moving said part from a position supplying fuel to one vaporizer to a position supplying fuel to a different vaporizer due to movement of said vessels from one to the other of said two positions, and means for supplying heat alternatively to one or the other of said vessels to vaporize the liquid in the vessel to which heat is being supplied.
- 55 6. In liquid fuel combustion apparatus, a plurality of vaporizers adapted to vaporize liquid fuel for combustion in a burner, a first system of parts movable to different positions to direct fuel to different vaporizers, a second system of movable parts including two communicating liquid containing vessels, said second system of parts being mounted to move to one or the other of two positions dependent upon the relative amounts of liquid in the two vessels, motion transmitting means including a lost motion connection for causing movement of said first system of parts from one to the other of its two positions due to movement of said second system of parts from one to the other of its two positions, and means for supplying heat alternatively to one or the other of said vessels to vaporize the liquid in the vessel to which heat is being supplied.
- 60 7. In liquid fuel combustion apparatus, two vaporizers adapted to vaporize liquid fuel for combustion in a burner, a first system of parts mounted to tilt to one or the other of two positions to direct fuel alternatively to one or the other of said vaporizers, a second system of parts comprising two communicating liquid containing vessels, said second system being mounted to tilt to one or the other of two positions dependent upon the relative quantity of liquid in the two vessels and including motion transmitting parts for causing movement of said first system of parts from one to the other of its positions upon movement of the second system of parts from one to the other of its positions, and means for supplying heat alternatively to one or the other of said vessels to vaporize the liquid in the vessel to which heat is being supplied.
- 65 8. In liquid fuel combustion apparatus, two vaporizers adapted to vaporize liquid fuel for combustion in a burner, a first system of parts mounted to tilt to one or the other of two positions to direct fuel alternatively to one or the other of said vaporizers, a second system of parts comprising two communicating liquid containing vessels, said second system being mounted to tilt to one or the other of two positions dependent upon the relative amount of liquid in the two vessels and including parts operatively associated with said first system to provide a lost motion connection between the two systems whereby to cause the first system to tilt from one to the other of its positions upon movement of the second system from one to the other of its positions, and means for supplying heat alternatively to one or the other of said vessels to vaporize the liquid in the vessel to which heat is being supplied.
- 70 9. In liquid fuel combustion apparatus, a burner comprising a metal base member providing two vaporizers adapted to be continuously heated by conduction of heat from the burner and to vaporize liquid fuel for combustion in the burner, a first system of parts mounted to tilt to one or the other of two positions to direct fuel alternatively to one or the other of said vaporizers, a second system of parts comprising two communicating liquid containing vessels mounted to tilt from one to the other of two positions dependent upon the relative amounts of liquid in the vessels and including parts operatively associated with said first system to cause movement of said first system from one to the other of its positions upon movement of
- 75 75

said second system from one to the other of its positions, and means for transmitting heat alternatively to one or the other of said vessels to vaporize the liquid in the vessel to which heat is being transmitted.

10. In liquid fuel combustion apparatus, a burner comprising a metal base member providing two vaporizers adapted to be continuously heated by conduction of heat from the burner and to vaporize liquid fuel for combustion in the burner, two heat transmitting members in heat receiving relation with said burner, a first system of parts mounted to tilt from one to the other of two positions to direct fuel alternatively to one or the other of said vaporizers, a second system of parts comprising two communicating liquid containing vessels mounted to tilt from one position in which one of the vessels is in heat transmitting relation with one of said heat transmitting members to a second position in which the other of said vessels is in heat transmitting relation with the other of said heat transmitting members, depending upon the relative amounts of liquid in said vessels, said second system including motion transmitting parts for causing movement of said second system of parts from one to the other of its positions to move said first system of parts from one to the other of its two positions.
20. In liquid fuel combustion apparatus, a burner comprising a metal base member providing two vaporizers adapted to be continuously heated by conduction of heat from the burner and to vaporize liquid fuel for combustion in the burner, two heat transmitting members in heat receiving relation with said burner, a first system of parts mounted to tilt from one to the other of two positions to direct fuel alternatively to one or the other of said vaporizers, and a second system of parts comprising two communicating liquid containing vessels mounted to tilt from one position in which one of the vessels is in heat transmitting relation with one of said heat transmitting members, depending upon the relative amounts of liquid in said vessels, said second system including motion transmitting parts for causing movement of said second system of parts from one to the other of its positions to move said first system of parts from one to the other of its two positions.
25. In liquid fuel combustion apparatus, a burner comprising a metal base member providing two vaporizers adapted to be continuously heated by conduction of heat from the burner and to vaporize liquid fuel for combustion in the burner, two heat transmitting members in heat receiving relation with said burner, a first system of parts mounted to tilt from one to the other of two positions to direct fuel alternatively to one or the other of said vaporizers, and a second system of parts comprising two communicating liquid containing vessels mounted to tilt from one position in which one of the vessels is in heat transmitting relation with one of said heat transmitting members, depending upon the relative amounts of liquid in said vessels, said second system including motion transmitting parts for causing movement of said second system of parts from one to the other of its positions to move said first system of parts from one to the other of its two positions.
30. 11. In liquid fuel combustion apparatus, a burner comprising a metal base member providing two vaporizers adapted to be continuously heated by conduction of heat from the burner and to vaporize liquid fuel for combustion in the burner, two heat transmitting members in heat receiving relation with said burner, a first system of parts mounted to tilt from one to the other of two positions to direct fuel alternatively to one or the other of said vaporizers, and a second system of parts comprising two communicating liquid containing vessels mounted to tilt from one position in which one of the vessels is in heat transmitting relation with one of said heat transmitting members, depending upon the relative amounts of liquid in said vessels, said second system including motion transmitting parts for causing movement of said second system of parts from one to the other of its positions to move said first system of parts from one to the other of its two positions.

the burner, two heat transmitting members in heat receiving relation with said burner, a first system of parts mounted to tilt from one to the other of two positions to direct fuel alternatively to one or the other of said vaporizers, a second system of parts comprising two communicating liquid containing vessels mounted to tilt from one position in which one of the vessels is in heat transmitting relation with one of said heat transmitting members to a second position in which the other of said vessels is in heat transmitting relation with the other of said heat transmitting members, depending upon the relative amounts of liquid in said vessels, said second system including motion transmitting parts for causing movement of said second system of parts from one to the other of its positions to move said first system of parts from one to the other of its two positions, and means for regulating the rate of heat transmission between said heat transmitting members and said vessels.

12. In liquid fuel combustion apparatus, a plurality of vaporizers adapted to vaporize liquid fuel for combustion in a burner and to be heated by heat derived from the burner, means for supplying liquid fuel alternatively to the different vaporizers, and means for actuating the first-mentioned means to cause fuel to be supplied to a different vaporizer at predetermined intervals including a plurality of liquid containing vessels and heating means deriving heat from the burner for alternatively heating said vessels to vaporize the liquid therein.

GUSTAF ERIK BJÖRKLUND.
